DESIGN FOR A CASSEROLE

Warner W. Hoople, Evanston, Ill., assignor to Club Aluminum Products Company, Chicago,
Ill., a corporation of Delaware

Application February 10, 1940, Serial No. 90,184

Term of patent 7 years

To all whom it may concern:

Be it known that I, Warner W. Hoople, a citizen of the United States and a resident of Evanston, county of Cook and State of Illinois, have invented a new, original, and ornamental Design for a Casserole, of which the following is a specification, reference being had to the accompanying drawing, forming a part thereof, and in which Fig. 1 is a perspective view of the casserole, showing my new design. Fig. 2 is a view in side elevation of the casserole, with its cover omitted, and Fig. 3 is a transverse vertical sectional view through the casserole, taken along line 3—3 of Fig. 2, with its cover in position thereon.

I claim:

The ornamental design for a casserole, substantially as shown.

WARNER W. HOOPLE.
